UNITED STATES PATENT OFFICE.

THOMAS McDONOUGH, OF CHICAGO, ILLINOIS.

TELLURIAN.

SPECIFICATION forming part of Letters Patent No. 268,512, dated December 5, 1882.

Application filed July 13, 1882. (No model.)

To all whom it may concern:

Be it known that I, THOMAS McDONOUGH, of Chicago, in the county of Cook and State of Illinois, have invented certain Improvements in Educational Globes, of which the following is a specification.

This invention relates more especially to improvements designed for use in connection with the apparatus for which Letters Patent of the United States were granted to me on the 28th day of February, 1882, No. 254,229, although certain of the improvements are also applicable to other apparatus of a similar character.

The improvements consist in means for imparting to the earth-globe a rotation upon its own axis during the time that it is revolving about the sun; in combining with the apparatus a miniature comet and means for maintaining the same with its tail constantly away from the sun while being carried around the same, and in diagrams arranged in relation to the revolving and non-revolving disks in such manner as to indicate the motion of the heavenly bodies in relation to each other.

Referring to the accompanying drawings, Figure 1 represents a vertical section through the center of the apparatus. Fig. 2 is a top plan view of the same. Fig. 3 is a diagram illustrating the gearing by which motion is imparted to the earth-globe and to the comet; Fig. 4, a view of the miniature comet.

A represents a stationary circular base-plate, provided at or near the outer edge with a circular face, *a*, provided with monthly divisions, the signs of the zodiac, &c., as in the original apparatus.

B represents a horizontal arm revolving upon a fixed axle at the center of the base A.

C represents a circular disk, secured rigidly on the axle of the arm B above the latter, as shown. D represents a second disk, preferably of the same size as the first, mounted and arranged to revolve horizontally upon the outer end of the arm B. The disks C and D are provided in their under edges with peripheral gear-teeth, and are connected by an intermediate pinion, E, mounted upon the arm B, as shown, so that when the arm is rotated horizontally it will carry the outer disk bodily around the central disk, C, and at the same time, through the intermediate pinion, E, cause the disk D to be rotated upon its own axis. In

place, however, of the gearing shown for transmitting motion to the outer disk, any other suitable appliances may be used for the same purpose. A simple substitute for the arrangement above described is that represented in dotted lines in Fig. 1, consisting simply of a grooved pulley, F, secured rigidly in place at the center of the apparatus, and a pulley, G, secured to the axis of the outer disk, D, the two pulleys being connected by means of a belt, H. The stationary central disk, C, is provided with a vertical standard or socket at the center to receive the earth or the sun globe, as occasion may require, and is also provided outside of the center with one or more inclined sockets or standards, *b*, to which the globes may be applied, as required. The outer rotating disk, D, is provided with an inclined revolving spindle, I, designed to sustain the globe J, representing the earth. The spindle I is seated loosely in a socket or bearing formed upon the disk D, and is provided on its lower end with an elastic pulley, K, engaging with and rotated by a circular rim or flange, L, which is formed on the outer end of the revolving arm B concentric with the disk D. As the disk D is rotated upon its own axis it causes the pulley K to travel around the inner surface of the ring or flange L, whereby the spindle I is caused to rotate and revolve the earth upon its own axis. It will thus be seen that as the earth-supporting spindle I is located eccentrically with reference to the disk D the earth receives a threefold motion: first, its motion bodily around the disk C; second, a motion bodily around the center of the disk D, whereby its path or orbit around the sun is rendered eccentric; and, third, the rotation upon its own axis.

While it is preferred to make use of the elastic pulley K, driven by frictional contact with the ring or flange L, a pinion may be substituted and the ring L provided with gear-teeth to act thereon. The elastic driving-wheel is preferred because of its cheapness and of the fact that it runs noiselessly, and also because it admits of the earth being readily turned by hand upon its axis, as is frequently necessary in order to secure the proper explanation of the phenomena represented by the apparatus.

For the purpose of illustrating clearly the motion of comets with reference to the sun, the representative of which will be located at such

time at the center of the disk C, as represented in Fig. 1, I provide the outer disk, D, with a vertical eccentrically-located revolving socket, M, sustaining a removable shaft or spindle, 5 which bears on its upperend a miniature comet, N, having a point and an expanded tail extending in opposite directions. The lower end of the socket M, I provide with a pinion, O, which gears into a pinion, P, journaled on the 10 under side of the disk D, the pinion P in turn engaging with and receiving motion from a central pinion, Q, secured rigidly on the arm B. The revolution of the arm B carries the disk D, and the comet sustained thereby, around 15 the sun. During this action the disk D revolves upon its own center on the arm B, and thus carries the pinions O and P around the pinion Q. The result of this action is that the pinions O, P, Q cause the comet-sustaining 20 socket M to revolve within the disk D in such manner that the comet is maintained with its tail constantly away from the sun while being carried around the same. This presentation of the comet constantly with its tail away from 25 the sun is an essential feature of my apparatus, and is a proper illustration of the theories now generally accepted as to the motion of comets.

While it is preferred to operate the comet by 30 means of three pinions, as described, it is manifest that other arrangements of driving-gear may be substituted therefor.

It will of course be understood that the comet-supporting spindle is removable from the 35 socket M, in which it is seated, and that each and all of the globes represented in the apparatus may be readily removed from their seats. The supports for the various globes may consist of standards or pins upon the disk to enter sockets in the globes, or, as in my previous 40 apparatus, the spindles attached rigidly to the globes and adapted to enter sockets on the disks.

For the purpose of facilitating the explanation of the phenomena illustrated by means of the apparatus, I provide the central stationary disk, C, with diagrams and graduations, as in the original apparatus; but instead of providing the outer disk, as before, with graduations similar to those on the central disk, I now provide it with a series of diagrams, such as shown in the drawings, illustrating the movement of the celestial bodies in reference to the earth. The character of these diagrams 55 upon the outer disk is clearly represented in Fig. 2, in which it will be seen that the orbits of the various planets are described concentrically, or substantially so, upon the outer disk.

I do not claim broadly the application of 60 planetary diagrams to disks or dials. It will be perceived that in my apparatus a peculiar and important relationship and co-operation exist between the diagrams arranged upon the 65 revolving disk D, as shown, and the other members of the apparatus, inasmuch as the diagrams are brought into such position and

moved in such manner with respect to the position and movement of the globe as to indicate clearly the changing relationship of the 70 various bodies.

In using the apparatus the earth-globe will be attached, as shown in Fig. 1, in a central or substantially central position over the center of the disk D, so that upon considering the 75 diagram in connection therewith the movements of the various planets with respect to the earth and the entire planetary system in respect to the sun will be readily understood.

An important feature of the apparatus consists in the fact that the outer disk having the plane diagrams thereon is revolved around the earth at the same time that the earth is revolved upon its own axis, and the earth and the diagrams both revolved around the sun, 85 which will be located at the center of the system.

Having thus described my invention, what I claim is—

1. In combination with the central globe representing the sun, the revolving arm B, provided with the rim or flange L, the disk D, mounted upon the outer end of the arm B, means, substantially as shown, for revolving the disk D upon its own axis, and the earth-globe having its spindle sustained by the disk D, and provided with a pulley engaging with the circular rim L, as shown.

2. In combination with the central globe representing the sun, the disk D, the earth-globe 100 J, sustained by an inclined axis upon the disk D, and means, substantially as described, for revolving the disk D upon its own axis, and also revolving the earth-supporting spindle within the disk.

3. In combination with the horizontal revolving arm B and the disk D, arranged to revolve thereon, the earth-globe J and its spindle I, provided with a frictional driving-pulley, K, arranged to co-operate with an annual 110 rim upon the arm B, substantially as shown.

4. In combination with the disk D, revolving upon its axis by means substantially as described, a revolving spindle mounted upon said disk to support the earth-globe, and a 115 frictional pulley and flange, substantially as described, for imparting motion to said spindle.

5. In combination with a globe or equivalent device representing the sun, a miniature comet 120 and mechanism, substantially as described, whereby the comet is revolved around the sun and maintained with its tail extended therefrom.

6. In combination with the revolving arm 125 B, the disk D, and means, substantially as described, for revolving said disk upon the arm, the comet-sustaining spindle M and the gear-wheels O P Q for operating the same, substantially as described and shown.

7. In combination with the sun-globe or its equivalent, the revolving arm B, disk D, the comet-sustaining spindle M, and means, substantially as described, for revolving the disk

D upon its own axis, and at the same time revolving the spindle M within the disk.

8. In an apparatus for illustrating the movements of the heavenly bodies, a device representing the sun, a device representing the earth arranged to revolve around the sun, and a disk provided with diagrams representing the movements of the planetary bodies in re-

lation to the earth, and means, substantially as described, for revolving said disk upon its own axis beneath the earth while being carried with the latter around the sun.
